UNITED STATES PATENT OFFICE.

SAMUEL M. VAUCLAIN, OF PHILADELPHIA, PENNSYLVANIA, ASSIGNOR TO
LOCOMOTIVE SUPERHEATER COMPANY, A CORPORATION OF NEW JERSEY.

SUPERHEATER.

1,034,540.

Specification of Letters Patent. Patented Aug. 6, 1912.

Application filed October 28, 1911. Serial No. 657,230.

To all whom it may concern:

Be it known that I, SAMUEL M. VAUCLAIN, a citizen of the United States, residing in Philadelphia, Philadelphia county, State of Pennsylvania, have invented certain new and useful Improvements in Superheaters, of which the following is a specification, reference being had to the accompanying drawings, which form a part hereof.

10 This invention relates generally to superheaters for locomotive and like boilers in which the superheater pipes are located in the fire-tubes of the boiler.

15 The object of the invention is to facilitate the withdrawal and replacement of any unit or single group of superheater pipes without disturbing the others.

In accordance with the invention each unit is secured at its ends to a chambered 20 plug which is secured with a steam tight joint in the header, being preferably tapered, and can be withdrawn from the forward end, taking with it the superheater unit. The chambers of the plug are provided with 25 ports for communication with the saturated and superheated steam chambers of the header respectively and the ends of the superheater pipes are so connected to the chambers as to cause the steam to circulate 30 through the pipes.

The invention will be more fully explained hereinafter with reference to the accompanying drawings in which it is illustrated and in which—

35 Figure 1 is a view partly in longitudinal central section of so much of a steam boiler as is necessary to enable the application of the invention thereto to be understood. Fig. 2 is a view of the same in end elevation. 40 Fig. 3 is a detail view in section showing one of the plugs in position in the header with its pipe connections. Fig. 4 is a detail view showing the arrangement of the pipes which constitute a unit and the connection 45 of the pipes at the fire-box end, the plane of section being indicated by the broken line 4—4 of Fig. 5. Fig. 5 is a detail view in section on the plane indicated by the line 5—5 of Fig. 4.

50 The invention is illustrated in the drawings as applied to a locomotive boiler of ordinary construction, the shell *a*, the fire-tube sheet *b*, the fire-tubes *c*, the saturated steam pipe *d*, and the superheated steam or delivery pipes *e* being all constructed and

arranged in any usual or suitable manner. The header *f*, which is located in the smokebox and is connected with the saturated steam pipe *d* and the superheated steam pipes *e* has a front wall *f'*, a rear wall *f''* and an intermediate wall *f'''* which form between them a saturated steam chamber *f⁴* and a superheated steam chamber *f⁵*, said chambers being connected respectively with the pipes *d* and *e*. In line with each fire-tube *c* the header is pierced, through it, three walls, with an opening, the minimum diameter of which is preferably as great as the outside diameter of the corresponding fire-tube. Preferably the opening through the walls of the header is formed on a taper and the chambered plug *g* which is inserted therein is correspondingly tapered to facilitate the formation of a steam tight joint. Each plug *g*, as shown most clearly in Fig. 3, has a removable cap or front end *g'*, a rear end or wall *g''*, and an intermediate wall *g'''*, these walls forming a chamber *g⁴*, corresponding to the chamber *f⁴* of the header, and a chamber *g⁵* corresponding to the chamber *f⁵* of the header. The chamber *g⁴* is provided with a port *g⁶* to afford communication with the chamber *f⁴* and the chamber *g⁵* is likewise provided with a port *g⁷* to afford communication with the chamber *f⁵*. The cap *g'* is preferably flanged as shown so that it may be secured to the header by bolts *h* *h'*, which may extend through all of the walls of the header or into the front wall only. One end of the corresponding superheater unit is secured to the plug *g* so as to communicate with the chamber *g⁴* and receive therefrom the saturated steam, as indicated at *i* in Figs. 1 and 3, while the other end of the unit is carried through a chamber *g⁴* and is connected to the plug in communication with the chamber *g⁵*, so as to deliver the superheated steam thereto, as indicated at *k* in Figs. 1 and 3. Tight joints between the ends of the superheater unit and the walls of the plug are made in the usual manner. The superheater pipes of each unit may be arranged in any suitable manner. Preferably, however, they are arranged as shown in the drawings, two pipes *i* being in communication with the saturated steam chamber *g⁴* at their forward ends and being connected at their rear ends, through a suitable union *l*, with a single return pipe *k*, which is connected at its for-

ward end with the superheated steam chamber g^s of the plug. This distribution of the saturated steam in two pipes i , severally of smaller diameter than the return pipe k , is found to give most satisfactory results in practice.

It will be obvious that any superheater unit can be removed readily without disturbing any other by the withdrawal of the corresponding plug g and that, if necessary, any one of the fire-tubes e may also be withdrawn without disturbing any other than the single superheater unit involved.

It will be understood that the details of construction and arrangement can be varied to suit different conditions of use and that the invention therefore is not limited to the particular construction and arrangement shown and described herein.

20 I claim as my invention:—

1. In a superheater for steam boilers, the combination of a header having a chamber for saturated steam and a chamber for superheated steam, a chambered plug removably secured in the header and having a chamber communicating with the saturated steam chamber of the header and a chamber communicating with the superheated steam chamber of the header, and a superheater unit having its ends communicating respectively with the respective chambers of the plug.

2. In a superheater for steam boilers, the combination of a header having a chamber for saturated steam and a chamber for superheated steam, a tapered chambered plug removably secured in the header and having a chamber communicating with the saturated steam chamber of the header and a chamber communicating with the superheated steam chamber of the header, and a superheater unit having its ends communicating respectively with the respective chambers of the plug.

45 3. In a superheater for steam boilers, the combination of a header having a front wall, a rear wall and an intermediate wall to form a chamber for saturated steam and a chamber for superheated steam, said walls being pierced with openings in line with the superheater unit, a chambered plug seated in said openings and having a chamber communicating with the saturated steam chamber of the header and a chamber communicating with the superheated chamber of the header and a superheater unit having its ends communicating respectively with the respective chambers of the plug.

60 4. In a superheater for steam boilers, the combination of a header having a front wall, a rear wall and an intermediate wall to form a chamber for saturated steam and a chamber for superheated steam, said walls being pierced with openings in line with the superheater unit, a chambered plug seated

in said openings and having a chamber communicating with the saturated steam chamber of the header and a chamber communicating with the superheated steam chamber of the header, and a superheater unit having one end extended into the rear chamber of the plug to communicate therewith and having another end extended through the rear chamber of the plug into the forward chamber thereof to communicate therewith.

5. In a steam boiler, the combination of a boiler shell, a fire-tube, a header located in front of the fire-tube and having a front wall, a rear wall and an intermediate wall to form a chamber for saturated steam and a chamber for superheated steam, said walls being pierced with openings in line with the fire-tube, a chambered plug seated in said openings and having a chamber communicating with the saturated chamber of the header and a chamber communicating with the superheated steam chamber of the header, and a superheater unit disposed in the fire-tube and having its ends communicating respectively with the respective chambers of the plug.

6. In a superheater for steam boilers, the combination of a header having a front wall, a rear wall and an intermediate wall to form a chamber for saturated steam and a chamber for superheated steam, said walls being pierced with openings in line with the superheater unit, a chambered plug seated in the openings in the intermediate and rear walls, means to close the opening in the front wall, and a superheater unit having one end extended into the chamber of the plug to communicate with the corresponding chamber of the header and another end extended through said chamber of the plug to communicate with the other chamber of the header.

7. A superheater unit comprising a plurality of pipes to receive the saturated steam, a single return pipe, and a union connecting the saturated steam pipes with the return pipe.

8. In a superheater for steam boilers, the combination of a header having a chamber for saturated steam and a chamber for superheated steam, a superheater unit comprising a plurality of pipes communicating with the saturated steam chamber of the header, a single return pipe communicating with the superheated steam chamber of the header, and a union connecting the saturated steam pipes with the return pipe.

9. In a superheater for steam boilers, the combination of a header having a chamber for saturated steam and a chamber for superheated steam, a chambered plug removably secured in the header and having a chamber communicating with the saturated steam chamber of the header and a chamber

communicating with the superheated steam chamber of the header, and a superheater unit comprising a plurality of pipes communicating with the saturated chamber of the plug, a single pipe communicating with the superheated steam chamber of the plug, and a union connecting the saturated steam pipe with the return pipe.

This specification signed and witnessed this 14th day of October A. D., 1911.
